UNITED STATES PATENT OFFICE.

WILLIAM L. MYERS, OF INDUSTRY, ILLINOIS, ASSIGNOR OF ONE-HALF TO
JAMES SCUDDER, OF INDUSTRY, ILLINOIS.

STIRRUP.

SPECIFICATION forming part of Letters Patent No. 746,126, dated December 8, 1903.

Application filed August 15, 1903. Serial No. 169,629. (No model.)

To all whom it may concern:

Be it known that I, WILLIAM L. MYERS, a citizen of the United States, residing at Industry, in the county of McDonough and State 5 of Illinois, have invented a new and useful Stirrup, of which the following is a specification.

This invention relates to certain improvements in stirrups, and has for its principal 10 object to provide a stirrup of simple and economical construction, consisting of few parts, and capable of adjustment to any desired position to facilitate mounting.

A further object of the invention is to provide a stirrup that may be adjusted to facilitate mounting and in which the stirrup will remain in the position to which it is adjusted without the necessity of holding the stirrup or stirrup-strap while the rider is mounting. 15

A still further object of the invention is to provide an improved form of stirrup in which the stirrup proper is yieldably mounted or suspended in such manner that the rider may rise from the animal without being subjected 20 to any jar or strain, and, further, in which provision is made for adjusting the yieldable connection in accordance with the weight of the rider.

With these and other objects in view, as 25 will more fully hereinafter appear, the invention consists in the novel construction and arrangement of parts hereinafter described, illustrated in the accompanying drawings, and particularly pointed out in the appended 30 claim, it being understood that various changes in the form, proportions, size, and minor detail of the structure may be made without departing from the spirit or sacrificing any of the advantages of the invention.

In the accompanying drawings, Figure 1 is 35 a perspective view of the stirrup constructed in accordance with the invention. Fig. 2 is a longitudinal sectional elevation of the same. Fig. 3 is a detail perspective view of the top 40 piece of the stirrup detached.

Similar numerals of reference are employed 45 to indicate corresponding parts throughout the several figures of the drawings.

In the drawings, 1 designates the ordinary loop, usually formed of a strip of wood. The 50 upper ends of the loop are connected to a cross-bar 2, that is formed, preferably, of a single piece of sheet metal die-shaped or otherwise formed in such manner as to firmly engage the ends of the loop. The main body 55 portion of the cross-bar is substantially rectangular in form, and its opposite ends are bent downward, forming flanges 3 for engagement with the inner surface of the loop ends. At the opposite ends of both flanges are ears 60 4, that are bent around the outer edges of the loop and are then secured in place by rivets or other securing devices, as indicated at 5. The securing devices are preferably extended through both the ears, the loop ends, and 65 the flanges 3, so that the ends of the loop may be firmly and positively clamped and held in place, movement in any direction independent of the cross-bar being rendered impossible.

At the center of the cross-bar is an opening 70 for the passage of a shank or stem 6 of the stirrup-strap-attaching loop 7. The lower end of the shank or stem is threaded for the reception of an adjustable nut 8, and between the top of this nut and the inner surface of 75 the cross-bar is arranged a helical compression-spring 9, that normally tends to keep the stirrup-loop in elevated position, excessive movement being prevented by the contact of a washer 10, surrounding the shank or stem, 80 with the lower portion of the stirrup-strap-attaching loop.

In mounting the stirrup may be readily turned, with the shank or stem as a center, until the stirrup-loop is in a position convenient 85 for the insertion of the foot of the rider, and owing to the frictional strain exerted by the spring on the under surface of the cross-bar the stirrup will be maintained in any position to which it may be adjusted, thus rendering 90 it unnecessary to hold the stirrup in position during mounting, as is often necessary in the use of stirrups of ordinary construction. Should the rider wish to rise from the back of the animal, he may stand up in the stirrups, and his weight will be borne by the 95

springs, yielding connection preventing the jar and strain usually experienced with stirrups of ordinary construction.

Having thus described the invention, what is claimed is—

In a stirrup, the combination with a stirrup-loop, of a metallic cross-bar for connecting the upper ends of the loop, said cross-bar having opposite depending end flanges for engaging the inner faces of the loop and the opposite ends of said flanges being provided with ears

embracing the edges and outer faces of the loops to thereby prevent lateral play in any direction, and securing devices passing through the ears, the loop ends and the flanges. 15

In testimony that I claim the foregoing as my own I have hereto affixed my signature in the presence of two witnesses.

WILLIAM L. MYERS.
